UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR SPOONS, &c.

SPECIFICATION forming part of Design No. 25,855, dated August 4, 1896.

Application filed June 29, 1896. Serial No. 597,479. Term of patent 7 years.

To all whom it may concern:

Be it known that I, HENRY L. WALLACE, of Wallingford, in the county of New Haven and State of Connecticut, have invented a new Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification and represents a face view of a handle embodying my design.

This invention relates to a design for the handles of spoons, forks, and like articles of table-service; and the design consists in the configuration and ornamentation as shown in the accompanying illustration.

As herein shown, the handle tapers upward from the bowl to a point near its outer end, where it curves inward and then outward, forming an oval tip A, surmounted by a shell-like ornament B. Starting from this

shell-like ornamentation scrolls C curve inward, following the contour of the handle to a slight outward curve D, where they terminate and are met by elongated scrolls E, which follow the outline of the handle downward to the bowl, curving slightly outward at their juncture with the bowl. These scrolls inclose a plain panel corresponding in outline to the contour of the complete handle, all as shown in the accompanying illustration.

I claim—

The design for the handles of spoons, forks &c., as described and shown in the accompanying illustration.

In testimony whereof I have signed this specification in the presence of two subscribing witnesses.

H. L. WALLACE.
